(57) **CLAIM**

The ornamental design for a tailgate television stand, as shown and described.

DESCRIPTION

FIG. 1 is a front perspective view of my new design in a closed position;

FIG. 2 is a front perspective view of my new design in an open state;

FIG. 3 is a rear perspective view of FIG. 2;

FIG. 4 is a side elevational view of FIG. 1;

FIG. 5 is a side elevational view of FIG. 2; and,

FIG. 6 is a rear elevational view of FIG. 2.

The broken lines are for environmental purposes only and form no part of the claimed design.
